(57) **CLAIM**

The ornamental design for a puzzle game, as shown and described.

DESCRIPTION

The patent file contains at least one drawing executed in color. Copies of this patent with color drawing(s) will be provided by the Office upon request and payment of the necessary fee.

FIG. 1 is a top view of a puzzle game according to the present disclosure.

FIG. 2 is a back, top, right side perspective view of the puzzle game of FIG. 1.

FIG. 3 is a back, top, left side perspective view of the puzzle game of FIG. 1.

FIG. 4 is a front, top, left side perspective view of the puzzle game of FIG. 1.

FIG. 5 is a front, top, right side perspective view of the puzzle game of FIG. 1.

FIG. 6 is a top view of another embodiment of a puzzle game according to the present disclosure.

FIG. 7 is a back, top, right side perspective view of the puzzle game of FIG. 6.

FIG. 8 is a back, top, left side perspective view of the puzzle game of FIG. 6.

FIG. 9 is a front, top, left side perspective view of the puzzle game of FIG. 6.

FIG. 10 is a front, top, right side perspective view of the puzzle game of FIG. 6.

FIG. 11 is a top view of another embodiment of a puzzle game according to the present disclosure.

FIG. 12 is a front, top, left side perspective view of the puzzle game of FIG. 11.

FIG. 13 is a back, top, left side perspective view of the puzzle game of FIG. 11.

FIG. 14 is a front, top, right side perspective view of the puzzle game of FIG. 11.

FIG. 15 is a back, top, right side perspective view of the puzzle game of FIG. 11.

(Continued)

FIG. 16 is a top view of another embodiment of a puzzle game according to the present disclosure. (56)

FIG. 17 is a back, top, right side perspective view of the puzzle game of FIG. 16.

FIG. 18 is a back, top, left side perspective view of the puzzle game of FIG. 16.

FIG. 19 is a front, top, left side perspective view of the puzzle game of FIG. 16; and,

FIG. 20 is a front, top, right side perspective view of the puzzle game of FIG. 16.

The colors shown in the drawings are part of the claimed design.
